The ornamental design for a rotating picture frame display, as shown.

DESCRIPTION

FIG. 1 is a front perspective view of the rotating picture frame display of the present invention;

FIG. 2 is a front view of the rotating picture frame display of FIG. 1;

FIG. 3 is a back perspective view of the rotating picture frame display of FIG. 1;

FIG. 4 is a top plan view in elevation of the rotating picture frame display of FIG. 1 with the inner frame further rotated;

FIG. 5 is a side view of the rotating picture frame display of FIG. 1, as seen from the right side of FIG. 2; and,

FIG. 6 is a partial cross-sectional view taken along line A-A of FIG. 4 of a molding of the inner frame of the rotating picture frame display of FIG. 1.

The broken line showing a photo illustration within the inner rotating frame is included for contextual purposes and forms no part of the claimed design.
